EXTRACTING TONGS

Frank Wright Hadley, Los Angeles, Calif.

Application December 4, 1944, Serial No. 566,481

1 Claim. (Cl. 294—103)

This invention relates to extracting tongs and more particularly to such a device adapted for the removal of objects from relatively narrow places.

A primary object of this invention is the provision of an improved tongs, adapted particularly for the removal of objects such as pickles, olives, or the like, from narrow neck bottles.

An additional object of the invention is the provision of such a pair of tongs adapted for any analogous use for removing any article from a relatively confined space.

Other objects reside in the combinations of elements, arrangements of parts, and features of construction, all as will be more fully pointed out hereinafter and disclosed in the accompanying drawing, wherein there is shown a preferred embodiment of this inventive concept.

In the drawing:

Figure 1 is a front elevational view of one form of device embodying features of this invention.

Figure 2 is a side elevational view of the device disclosed in Figure 1.

Figure 3 is a sectional view taken substantially along the line 3—3 of Figure 1, and

Figure 4 is a sectional view taken substantially along the line 4—4 of Figure 1 as viewed in the direction indicated by the arrows.

Like reference numerals refer to like parts throughout the several views of the drawing.

Having reference now to the drawing, there is generally indicated at 10 a member comprised of a handle portion 12 having inwardly turned flanges 13 extending a portion of its length. The lower portion of the member 10 is comprised of a right angularly disposed lug 14 having an aperture 15 centrally positioned therein, which aperture is adapted for the reception of a prong or point 16 carried on an angularly disposed lug 17 comprising the lower extremity of a member 18. The member 18 has an enlarged upper portion 19 adapted to fit snugly within the flanges 13 for longitudinal sliding movement therein. A projection 20 positioned at an intermediate point of the member 18, serves to facilitate sliding move-

ment thereof within grooves formed by the flanges 13.

From the foregoing the operation of the device should now be readily understandable.

The device is inserted in a narrow neck bottle or the like, and the object to be removed is grasped between the lugs 14 and 17, the projection 16 serving to impale the same. Pressure in a downward direction on the projection 20 now serves to tightly clamp the lugs 14 and 17 about the object to be withdrawn, whereupon the same may be readily removed from the bottle or the like.

Conversely upward pressure on the projection 20 serves to release the object by sliding the member 18 upwardly within the channels formed by the flanges 13 after the article has been removed from the bottle or the like.

From the foregoing it will now be seen that there is herein provided a device accomplishing all the objects of this invention and others including advantages of great practical utility and commercial importance, which is sturdy and durable in construction, reliable and efficient in operation, and relatively simple and inexpensive to manufacture and assemble.

As many embodiments may be made of this inventive concept, and as many modifications may be made in the embodiment hereinbefore shown and described, it is to be understood that all matter herein is to be interpreted merely as illustrative and not in a limiting sense.

I claim:

35 In a device of the character described, an extending member, flanges forming channels at one extremity thereof, a gripping element at the other extremity, a second member longitudinally slidable in said channels, and a gripping element opposed to said first-mentioned gripping element at the extremity of said second member, said gripping elements comprising opposed angularly disposed lugs, one of said lugs having an aperture therein, and the other having a projection thereon engageable with said aperture.

45 FRANK WRIGHT HADLEY.
